UNITED STATES PATENT OFFICE.

HUBERT J. HIGGINS, OF WARWICK, RHODE ISLAND.

FOLDABLE CONTAINER.

Application filed May 5, 1924. Serial No. 711,017.

To all whom it may concern:

Be it known that I, HUBERT J. HIGGINS, a citizen of the United States, residing at Warwick, in the county of Kent and State 5 of Rhode Island, have invented certain new and useful Improvements in Foldable Containers, of which the following is a specification.

My invention relates to foldable containers particularly adapted for cooking, baking and other shortening compounds.

The essential objects of my invention are convenience in packing and transport in a minimum of space; adaptability for application to triangular shaped contents; facility of manipulation in application to and removal from contents; security against accidental disengagement; and simplicity and inexpensiveness of construction.

My invention consists, therefore, in the means for producing the results above specified substantially as hereinafter claimed.

In the accompanying drawings illustrating the principle of this invention and the best mode now known to me of applying that principle.

Figure 1 is a diagram of the blank from which the container is constructed.

Figure 2, a perspective view of the blank 30 partially formed,

Figure 3, a like view of the same at a later stage of completion,

Figure 4, a front perspective view of the container completely folded, and

Figures 5 and 6, sections of the same on lines 5-5 and 6-6 respectively of Figure 4.

Like characters of reference indicate like parts throughout the views.

The blank is cut from a sheet of paper or other bendable material, preferably of paper board. The blank 7, as shown in rear elevation in Figure 1, is substantially rectangular in general outline and is provided near its bottom with a lateral, acute angular cavity 8, and opposite thereto a deeper lateral cavity 9 comprising a horizontal straight outer portion 10 and an acute angular inner portion 11. The uppermost corner 14 of the blank above the cavity 9 is curved or rounded. The upper margin of the blank is cut away from its edge inwardly to form an obtuse angular cavity 16, eccentric of the blank, and nearer the corner 14 than the opposite upper corner 17. The body is provided also with a diagonal slit or incision 19 continuous with one edge of the cavity 16, and with a second

slit 20 of equal length and parallel to the first slit extending from one side of the cavity 16. The cavities 8 and 9 form lateral ears or flaps 22 and 23; the cavity 16, cooperates therewith to form two upwardly diverging wings 24 and 25; and the slits 19 and 20 form a flap 26.

When the blank is composed of stiff material it is scored for folding. Two of the folding lines 30 and 31 extend parallel with each other and diagonally from the terminals of the incisions to the cavity 8. A diagonal line 33 extends from the apex of the cavity 9 to the corner 17 of the wing 24 and intersects the lines 30 and 31 at the terminals of the incisions. A second line 36 parallel with line 33 extends from the base of the acute angular portion of the cavity 9 to the cavity 16. A vertical line 37 extends from the end of the horizontal portion of the cavity 9 to the upper edge of the blank. A folding line 38 connects the apexes of the cavities 8 and 9, and vertical lines 39 and 40 extend from said apexes to the lower edge of the blank.

The lines 38, 39, and 40 bound the section 42 constituting the bottom of the container; and lines 39 and 40 define the ends of the side flaps 22 and 23. The triangular section 43 bounded by the lines 30, 33 and 38 constitutes the front wall of the box. Lines 30, 31, and 33 of the wing 24 bound the oblong diagonal section 44 constituting one side wall of the container. The triangular section of the wing 24 bounded by lines 31 and 33 constitutes the back 45 of the box. The slit 20 cooperates with the line 33 to form a foldable area 46 forming an inner section of the second side wall, which is adapted to retain the inturned flaps 26 and 23 which constitute an interior wall thickness. The oblong diagonal area 47 of the wing 25 bounded by the lines 33 and 36 constitutes an outer or overlapping portion of the second side wall. Lines 36 and 37 bound the triangular area 48 of the wing 25 which overlaps the back wall section 45 and constitutes an outer thickness thereof. The oblong laterally extending friction flap 49 upon the wing 25 having a square lower corner 50 will be hereinafter referred to.

In folding the container the blank rests with its back face uppermost as shown in Figure 1, and the triangular cake to be enclosed is laid thereon over the section 43 with which it peripherally registers, and

which constitutes the front wall of the receptacle. The horizontal strip or section 42, constituting in this instance the bottom of the receptacle, is now elevated against the bottom of the cake, and the flap extensions 22 and 23 are bent against the sides of the cake. The wing 24 is now elevated and brought towards the operator, and downwardly, and assumes during this bending 10 operation the position shown in Figure 2, the flap 26 being inwardly bent to be within the side wall 46 for engagement with the second side of the cake. Thus the body is formed with the triangular front 43 parallel 15 with the back 45, and the inclined sides 44 and 46 converge at the apex of the container. There is a resultant space or opening 51 between the bottom 42 and the adjacent edge of the back 45. The formation of the container is completed by bringing the wing 25 up and over the body and inserting the friction binding member or flap 49 in the opening 51 where it is frictionally held. The initial movement of which insertion is 20 shown in Figure 3, its square corner being first inserted. The rounded character of the corner 14 assists the entrance of the second end into the opening.

It is evident that in folding the original 30 blank 7 may initially be placed face down, as herein shown, or face up, in which case the front of the folded receptacle in one instance would be the back of the folded receptacle in the other instance, therefore, the 35 use of the words front or back in the claims will be read with such understanding.

I have entered into a detailed description 40 of the construction and relative arrangement of the parts embraced in the present embodiment of my invention in order to impart a full, clear, and exact understanding of the same. I do not desire to be understood as confining myself to the specific construction and relative arrangement of parts 45 shown as such changes or modifications may be made in practice as fairly fall within the scope of my invention as claimed.

I claim:

1. A triangular foldable container comprising a front, a back, a bottom, converging sides inclined relative to the bottom, and a member upon the front overlapping one side and the back and having a binding flap entirely concealed within the container.

2. A foldable triangular container comprising a front, a back, a bottom converging sides inclined relative to the bottom, and a member integral with the front overlapping one side and the back and having a binding flap entirely concealed within the container.

3. In a foldable container, a triangular front, a bottom, a triangular back spaced

from the bottom, sides inclined with relation to the bottom and to each other, and a member carried by the front comprising a portion overlapping one side and the back, and having a friction flap insertable in the space between the back and bottom.

4. A foldable container in a single piece, comprising a front, a back, a bottom, flaps upon the bottom, converging sides enclosing the flaps, and a member enclosing one of the sides and the back and said member having a flap frictionally engaged and entirely concealed within the container.

5. In a foldable container, a triangular front, a bottom integral with the front, an inclined side integral with the front, a triangular back integral with said side, a second inclined side integral with the back, and a member in one piece with the front overlapping the second side and the back and having a binding flap entirely concealed within the container.

6. In a foldable container, a triangular front, a bottom integral with the front, lateral lugs on the bottom, an inclined side integral with the front enclosing one flap, a flap on the inclined side, a triangular back integral with said side, a second inclined side integral with the back enclosing the second flap on the bottom and the flap on the side, and a member integral with the front enclosing the second side and back and having a binding flap entirely concealed within the container.

7. A foldable triangular container comprising a front, a bottom, a back spaced from the bottom, inclined sides, and a transversely inclined member integral with the front comprising a portion overlapping one side and the back, and a lateral friction flap insertable in the space between the back and bottom.

8. A foldable triangular container comprising a front, a bottom, a back spaced from the bottom, inclined sides, and a transversely inclined member carried by the front comprising a portion overlapping one side and the back and a lateral friction flap insertable in the space between the back and bottom and provided with a rounded end.

9. A blank for a foldable triangular container, cut to form a substantially rectangular body provided near its bottom with a lateral acute angular cavity and oppositely thereto with a deeper angular cavity, and with an obtuse angular cavity in its upper edge eccentric of the blank and having parallel incisions extending from the last mentioned cavity.

In testimony whereof I have affixed my signature.

HUBERT J. HIGGINS.
